PAIR OF SPECTACLES

Albert C. Petitto, Hudson, Mass., assignor to Foster Grant Co., Inc., Leominster, Mass., a corporation of Delaware

Filed Jan. 10, 1964, Ser. No. 78,153

Term of patent 14 years

(Cl. D57—1)

FIG. 1 is a front perspective view of a pair of spectacles showing my new design;

FIG. 2 is a rear perspective view thereof;

FIG. 3 is a front elevational view thereof;

FIG. 4 is a top plan view thereof; and

FIG. 5 is a side elevational view thereof.

The temples are shown broken away in FIGS. 2, 4, and 5 for convenience of illustration.

The dominant features of my design reside in those portions shown in solid lines.

I claim:

The ornamental design for a pair of spectacles, substantially as shown and described.
